UNITED STATES PATENT OFFICE

159,644

OPEN FRONT DISPLAY CABINET

Fred B. Keuthan and Fred W. Keuthan, Indianapolis, Ind., assignors to The Sargent-Gerke Co., Indianapolis, Ind., a corporation

Application March 24, 1949, Serial No. 1,586

Term of patent 7 years

(Cl. D80—11)

To all whom it may concern:

Be it known that we, Fred B. Keuthan and Fred W. Keuthan, citizens of the United States and residents of Indianapolis, county of Marion, and State of Indiana, have invented a new, original, and ornamental Design for an Open Front Display Cabinet, of which the following is a specification, reference being had to the accompanying drawing, forming part thereof.

In the drawing, Fig. 1 is a front perspective view of an open front display cabinet showing our new design.

Fig. 2 is a top plan view thereof.

Fig. 3 is a transverse sectional view thereof.

We claim:

The ornamental design for an open front display cabinet, substantially as shown.

FRED B. KEUTHAN.

FRED W. KEUTHAN.
